UNITED STATES PATENT OFFICE.

EDMUND L. ZALINSKI, OF UNITED STATES ARMY, ASSIGNOR TO THE PNEUMATIC DYNAMITE GUN COMPANY, OF NEW YORK, N. Y.

GAS-PRESSURE GUN AND METHOD OF OPERATING THE SAME.

SPECIFICATION forming part of Letters Patent No. 429,988, dated June 10, 1890.

Application filed May 6, 1884. Renewed May 14, 1890. Serial No. 351,733. (No model.)

To all whom it may concern:

Be it known that I, EDMUND L. ZALINSKI, lieutenant of artillery, United States Army, have invented certain new and useful Improvements in Gas-Pressure Guns and Methods of Operating the Same, of which the following is a specification, reference being had therein to the accompanying drawings.

This invention relates to gas-pressure guns for throwing projectiles and other missiles, and to methods for developing pressure by combustion in a receiver outside the bore of the gun.

The invention consists, first, in producing a pressure within a closed vessel by burning therein or in a chamber connected therewith gunpowder or other rapidly-burning combustible, and afterward admitting the same into the barrel of a gun behind the projectile; second, in producing a predetermined pressure within a closed vessel by burning therein or in a chamber connected therewith, gunpowder or other rapidly-burning combustible, and when such predetermined pressure is attained admitting the same into the barrel of a gun behind the projectile; and, third, in interposing a cooling medium between the developing-chamber and the barrel.

In order that others may understand and practice my invention, I will proceed to describe the same in connection with an apparatus for the projection of shells containing dynamite or other explosives, although said apparatus is equally applicable to the projection of other missiles.

In the drawings, Figure 1 is a side elevation of a gun, storage-flask, developing-chamber, and intermediate cooler. Fig. 2 is a longitudinal section of a developing-chamber with a cartridge-holder attached. Fig. 3 is a similar section of a developing-chamber with a series of cartridge-holders. Fig. 4 is an end elevation of Fig. 3.

A indicates the gun, of any usual construction, for gas-pressure or pneumatic cannon. B is the gas-flask therefor, which may be provided with a pressure-gage and safety-valve, as usual.

C is the inflow-pipe to the gas-flask. This

pipe will preferably pass in the form of a coil through a water-chamber D, so that the surplus heat may be extracted from any gas passing through the pipe.

E indicates the developing-chamber, which is a strong receiver, as of steel, capable of enduring several thousand pounds internal pressure. This chamber should also have a pressure-gage and safety-valve. A reducing valve at e and a cut-off valve at f will permit the regulation of the pressure in flask B to a predetermined amount, no matter how high the pressure may rise in chamber E. The chamber E has one, two, or more projecting bosses or cartridge-seats F, which are internally screw-threaded, and are preferably provided with stop-cocks G.

H indicate strong steel or similar metallic cartridge-cases. These cartridge-cases are screw-threaded at one end, so as to be secured firmly into the bosses F.

The interior of cartridge-cases H can be allowed to communicate with the interior of chamber E, when the cartridge-cases are screwed home and the cocks G are opened. By closing the cocks, however, communication between the cartridge-cases and the adjacent chamber is cut off. The cartridge-cases are preferably cylindrical, with an external screw-thread at the open end.

Each cartridge-case is to be filled with a slow-burning cartridge of rocket composition, slow-burning picrate composition, or other equivalent composition, which evolves a large quantity of fixed gas. The cartridge-cases are of small interior diameter, and the composition is firmly pressed into them, so as to secure slow combustion.

At the mouth of each cartridge-case, when screwed home in its seat, there is an apparatus for igniting the cartridge, which may be a nipple or fuse, or an insulated wire n, connected with a battery o, so that the composition in the cartridge-case may be ignited when desired.

When there are several cartridge-cases for one developing-chamber, as in Figs. 3 and 4, one or more may be removed and replaced at any time without disturbing the others.

The operation of the device is as follows:

80

75

100

The parts being supposed to be connected after the manner indicated in Fig. 1, a cartridge of powder or other combustible is placed in one of the cases H and ignited. The 5 gas developed by the combustion enters the chamber E, and through a connecting-pipe to the gas-flask B, which may be regulated by the reducing-valve e whenever the pressure in said chamber rises above that determined 10 as the proper pressure for the flask B, or whenever the pressure in said flask falls below the desired point. The gas in its passage from the developing-chamber may be cooled by passing through the coil in tank D; or the 15 coil, and also the flask B, may be dispensed with, the principle of operation being the same whether the cooling be resorted to or not, or whether the gas be drawn direct from the developing-chamber.

20 The cartridges packed for transportation can be quickly supplied, and whenever the pressure in the developing-chamber E is reduced it may be raised by the combustion of a new cartridge.

25 The gas from the flask B or developing-chamber E is admitted to the gun for discharging the projectile through a valve in a manner usual in pneumatic cannon.

In this application I have claimed my 30 method of operation of my invention, and described in connection therewith an apparatus by which such method may be practiced, and in another application, Serial No. 197,370, filed April 1, 1886, I have described and 35 claimed such apparatus with modifications, the invention being presented in separate ap-

plications in accordance with the rules of practice made and provided.

Therefore, what I claim, and desire to herein secure by Letters Patent, is—

1. The improvement in the art of gunnery, which consists in generating a gaseous pressure within a chamber closed with respect to the barrel of the gun and independent of the gun by burning therein or in a chamber connected therewith gunpowder or other rapidly-burning combustible, and then admitting the same into the barrel of the gun at the rear of the projectile, whereby the same is expelled from the barrel. 40

2. The improvement in the art of gunnery, which consists in generating a gaseous pressure within a chamber closed with respect to the barrel of the gun and independent of the gun by the combustion of a removable cartridge in a separate communicating-chamber, and then admitting the gas to the barrel of the gun under a predetermined pressure. 45

3. The improvement in the art of gunnery, which consists in generating a gaseous pressure within a chamber closed with respect to the barrel of the gun by burning gunpowder or other rapidly-burning combustible, and then passing said gas through a cooling medium before admitting the same to the barrel 60 of the gun. 65

In testimony whereof I affix my signature in presence of two witnesses.

EDMUND L. ZALINSKI.
